United States Patent Office

Des. 234,052

Patented Jan. 7, 1975

234,052

CEILING TILE

Joseph E. Sienkiewicz, Lancaster, Pa., assignor to
Armstrong Cork Company, Lancaster, Pa.

Filed Mar. 26, 1973, Ser. No. 344,943

Term of patent 14 years

Int. Cl. D25—01

U.S. Cl. D18—2 B

Fig. 1

Fig. 2

FIG. 1 is a top plan view of a ceiling tile showing my new design; and

FIG. 2 is a sectional view thereof taken along the lines II—II of FIG. 1.

I claim:

The ornamental design for a ceiling tile, substantially as shown.
